FEED MECHANISM FOR DISK RECORDING MACHINES

Lincoln Thompson, Cheshire, Conn.

Application April 23, 1936, Serial No. 75,923

10 Claims.

(CL 274—13)

This invention relates to the art of sound recording, and more particularly to a machine for recording sound on soft disk records having means for producing a uniform spiral track on the record without unevenness due to backlash.

One object of this invention is to produce a sound recording machine of the above nature having a swinging recording arm which is fed slowly across the record by means of a worm drive receiving power at greatly reduced speed from the turntable shaft.

A further object is to provide a recording machine of the above nature in which the backlash between the driving mechanism and the recording arm is taken up by a pair of differential friction slipping units.

A further object is to provide a sound recording machine of the above nature which will be simple in construction, inexpensive to manufacture, easy to install and manipulate, compact, rugged, precise, ornamental in appearance, and durable in use.

With these and other objects in view, there has been illustrated on the accompanying drawings one form in which the invention may be conveniently embodied in practice.

In the drawings:

Fig. 1 represents a perspective view of the disk recording machine as it appears when in operation.

Fig. 2 is a side elevation of the recording arm and the driving mechanism therefor, with a portion of said arm broken away to show the interior construction.

Fig. 3 is a vertical transverse sectional view of the driving head of the radial recording arm, the view taken along the line 3—3 of Fig. 2.

Fig. 4 is a horizontal sectional view of the same, the view taken along the line 4—4 of Fig. 3 looking in the direction of the arrows.

Fig. 5 is a vertical sectional view taken along the line 5—5 of Fig. 2, showing a portion of the driving mechanism and the turntable spindle.

Fig. 6 is a horizontal sectional view of the same, the view being taken along the line 6—6 of Fig. 5.

Fig. 7 is a transverse sectional view of the recording arm taken along the line 7—7 of Fig. 2, and showing the micrometer adjustable counter-balance mechanism for the cutting head.

In the recording of spoken messages as well as music it is often desirable to condense as many words or sounds on the record as possible, necessitating quite close spacing of the grooves or tracks, the number of such grooves often ex-

ceeding 150 per inch. In previous machines for recording on disk records, the spacing of the grooves or tracks was apt to be uneven due to backlash in the radial feed mechanism, resulting in an unsatisfactory reproduction of the message, running together of grooves, as well as difficulty in keeping the reproducing needle in the groove. By means of the present invention, the above and other disadvantages have been overcome.

Referring now to the drawings in which like reference numerals denote corresponding parts throughout the several views, the numeral 10 indicates the top of a phonograph recording cabinet having an electric motor, not shown, for driving a large horizontal grooved pulley 11 attached to the lower end of a vertical spindle 12 (see Fig. 2). The upper end of the spindle 12 extends through the top 10 of the cabinet and carries a turntable 13 upon which is adapted to rest a disk record 14 to be embossed or cut. Pivots mounted in one corner of the top 10 of the cabinet at one side of the turntable 13 is a radial recording arm 15 which is connected at its inner end to a driven power head 16 passing upwardly through a circular aperture 17 in the cabinet top 10 and adapted to swing said arm 15 slowly across the record 14.

The opposite or free end of the radial arm 15 supports a recording or cutting head 18 which is adjustably and pivotally secured thereto in a manner to be later described, and said head carries a detachable stylus 19 for producing the sound track in the record.

The transmission of power from the motor to the radial arm 15 is effected through a pair of gear boxes designated A and B (Fig. 2). The gear box A is associated with the drive spindle 12, while the gear box B is associated with the power head 16. The vertical drive spindle 12 (Fig. 5) is journaled in a vertical bearing bushing 20 having a relatively large flanged disk 20a integral with the upper end thereof and rigidly attached to the underside of the cabinet top 10, as by screws 21 (Fig. 2).

The spindle 12 is provided intermediate its length with a worm 22 which is adapted to intermesh with a worm gear 23 positioned in a vertical plane and enclosed in a square housing 24 located adjacent the bushing 20, said housing being attached to the underside of the flanged disk 20a. A cover member 25 (Figs. 2 and 6) closes the open end of the square housing 24 and is held in place by horizontal screws 26 positioned in the corners thereof.

The worm gear 23 is made rigid to a short stud shaft 27 by means of a transverse pin 28, said shaft 27 being suitably journaled in a pair of flanged bushings 29 and 30 located respectively in the housing 24 and the cover member 25. The rotation of the worm gear 23 is adapted to be opposed by a pair of frictional slipping disks 31 and 32 positioned on opposite sides of said gear wheel 23, each of said disks being formed of a series of built up leather washers. The pressure of the disks 31 and 32 against the opposite sides of the gear wheel 23 is controlled by means of the adjustable cover plate 25 which engages against the adjacent friction disk 32 and is preferably positioned in a slightly spaced relation from the square housing 24 and adapted to be adjustably drawn thereagainst by means of the binding screws 26 previously mentioned. It is to be understood, however, that the friction disks 31 and 32 may in some cases be dispensed with if desired, within the general spirit and scope of the invention.

One exposed end of the stud shaft 27 is fixed to one end of a horizontal elongated tubular shaft 33 by a pin 34 (see Fig. 6). The opposite end of the shaft 33 is connected to a stud shaft 35 in the gear box B by a transverse pin 36 (see Fig. 4). The stud shaft 35 carries a worm 37 which is rotatable in a suitable bore 38 of a gear housing block 39, and said shaft 35 is adapted to enter said bore through a flanged bearing bushing 40.

The worm 37 intermeshes with a large horizontal worm gear 41 (Figs. 3 and 4) keyed to a vertical driving spindle 42 of the power head 16 by means of a tapered pin 43. The worm gear 41 is positioned within a horizontal cylindrical socket 44 formed within the housing block 39, and said socket 44 is adapted to be closed by a cover plate 45 superimposed thereupon and serving as a journal for the upper end of the shaft 42. The lower end of the shaft 42 is suitably journaled in a flanged bushing 46 provided in a suitable aperture in the block 39.

A relatively heavy flat elongated tie plate 47 is attached to the underside of the housing block 39 by means of a plurality of long vertical screws 48 passing through said plate 47 and said block 39, and being threadedly engaged in aligned tapped holes in the cover plate 45. The tie plate 47 serves to connect the gear box B with the gear box A and is supported upon the underside of the cabinet top 18 by means of a pair of spaced hanger blocks 49 and 50, as shown in Fig. 2.

As shown in Fig. 3, the upper end of the driving spindle 42 has a flat plate 51 rigidly secured thereto by means of a transverse pin 52, and a relatively thick frictional disk 53 is interposed between said plate 51 and the cover plate 45. The disk plate 51 is adapted to be pulled downwardly at all times against the friction disk 53 by means of a strong helical spring 54 surrounding a lower reduced portion 55 of the spindle 42. The upper end of the spring 54 abuts against the flanged bushing 46 while the lower end abuts against a washer 56 and an adjusting nut 57 mounted on a threaded section of the reduced portion 55 of the spindle, whereby the pressure of said plate 51 upon the friction disk 53 may be manually adjusted as desired.

The friction plate 51 is provided on its outer edge with an upstanding integral flange 58 which serves to define a seat for the power head or hub 16, the latter having an interior hollow chamber

59, and being attached to said plate 51 by means of screws 60, 61, as shown in Fig. 3. The rear end of the radial arm 15 is superimposed on the hub 16 and is adjustably held thereagainst by means of a flanged stud 62 having a reduced 5 threaded end 63 projecting down into the hollow chamber 59.

A thin friction disk 64 is interposed between the radial arm 15 and the hub 16, and said arm is pressed downwardly against said friction disk 64 by a coiled spring 65 surrounding the reduced end 63 of said stud 62, the pressure of said spring being sufficient to cause the arm 15 to be driven by the hub 16. The upper end of the spring 65 abuts against a washer 66 mounted on said stud 62 and disposed against the upper end of the chamber 60, while the lower end of said spring 65 engages against a washer 67 seated upon an adjustable nut 68, the latter being employed to vary the tension of the spring as may be desired. 20

The friction between the arm 15 and the disk 64 is relatively weak as compared with the friction between the plate 51 and the friction disk 53, so that said arm 15 may be manually swung laterally in any direction without disturbing the 25 position of the hub 16 or the intermeshing of the gear 41 and worm 37. However, the friction exerted by the washer 64 is strong enough to prevent slippage of the arm 15 with respect to the hub 16, when the latter is slowly driven by the 30 feed mechanism.

It will be understood that this differential friction arrangement is of great importance in the practical recording of dictation, telephone conversations, and radio programs. It is of particular importance where the recording is interrupted from time to time and must be started up quickly without permitting the needle to leave the groove where the cutting is taking place. If the friction between the recording arm 15 and the friction slipping disk 64 was not weak compared to the friction between the plate 51 and the disk 53, the swinging of the arm 15 would cause play in the transmission between the turntable spindle 12 and the recording arm. This 45 play would necessarily have to be taken up before the recording arm would start to feed, which would introduce a time lag or delay in the recording. If such a backlash occurred, the stylus might grind around in the same groove and spoil both the blank and the stylus. Furthermore, such a delay would introduce an element of waiting which could not be tolerated in the recording of passing events, such as radio programs, 50 telephone conversations, etc.

By means of the present invention, the cutting of the record will always commence immediately as soon as the stylus is dropped into the groove, and the stylus will be positively positioned in said groove without loss of time even when the apparatus is used by unskilled operators. 60

A further advantage of the present machine is that it will record the programs with perfect fidelity even though there may be slight inaccuracies in the gears. This is due to the fact 65 that the worm will always be held tightly in mesh with the teeth of the gear, and there will be no evidence whatsoever in the spiraling of the record of the point at which one tooth of the worm leaves and the next tooth takes hold, which would 70 be the case if the friction slipping means 63 were not employed.

The ratio of the teeth on the two sets of intermeshing gears in the boxes A and B is 100 to 1 in each instance, whereby a reduction in speed of 75

10,000 to 1 is produced; that is, the turntable will rotate at a speed 10,000 times as fast as the angular velocity of the swinging recording arm 15.

In the making of records by either the cutting or indenting method, it is very essential that the weight of the recording head carrying the stylus be accurately and minutely adjusted, this being accomplished by the following construction:

As best shown in Figs. 1 and 2, the outer end 10 of the arm 15 is provided with a rigid short U-shaped bracket 69, in which is pivoted a hinged block 70 by means of a pin 71. The forward end of the block 70 is provided with an upwardly and rearwardly inclined rigid flat plate 72 adapted 15 to receive a slidable channel plate 73 which is adapted to be secured in any desired vertical position with respect to said bracket 69 by means of a bolt 74 secured to said plate 72 and extending through an elongated slot 75 in said plate 73. 20 A channel-shaped plate 76 attached to the cutting head 18 is pivoted at its lower ends to the slidable plate 73 by means of a pair of opposed binding screws 77. This construction permits the recording head 18 to be adjusted to any desired 25 angular position in respect to the channel plate 73.

The weight of the head 18 and its complementary supporting members is adapted to be counter-balanced by means of the force exerted 30 by a longitudinal horizontal arm 78 attached, as by short screws 78a, to the underside of the hinged block 70, and extending rearwardly to a point intermediate the length of the arm 15. The rear end of the arm 78 has riveted thereto an 35 upright post 79 which is adapted to pass up through an aperture 79a in the arm 15 and terminates in a rearwardly bent end 80.

A tension spring 81 is anchored at its upper end to the bent end 80, while the lower extremity of a 40 said spring is fastened to the forward end of a small vertical triangular plate 82 pivotally connected to the elevated horizontal arm 82a of an angle bracket 83 by means of a horizontal screw 84. As clearly shown in Figs. 2 and 7, the angle bracket 83 is attached to one side of the radial arm 15 by means of a horizontal screw 85 and extends upwardly and over the top of said arm 15.

In order to vary the tension of the counter-balancing spring 81, provision is made of a vertical adjusting screw 86 which threadedly engages in a tapped hole in the horizontal arm 82a of the angle bracket 83 and is provided with a knurled manually-operated head 86a at its upper end. The lower end of the screw 86 is provided with a spool 87, the two flanges of which embrace a lateral pin 88 projecting from the inside of the triangular plate 82 at the inner end thereof (see Fig. 7).

From the above construction, it will be seen that by screwing the adjusting screw 86 upwardly, the triangular plate 82 will be swung about its pivot in such a manner as to increase the tension of the spring 81, and consequently decrease the force with which the stylus 19 of the recording head 18 engages the record 14. By turning the screw 86 downwardly, the reverse action will take place; i. e., the tension of the spring 81 will be lessened, and the stylus pressure on the record will be increased due to the weight of the recording head 18.

In case it is desired to temporarily hold the recording head 18 in elevated inoperative position with the stylus 19 out of contact with the record 14, provision is made of a vertical up-standing pin 89 attached to an intermediate part

of the counter-balance arm 78, and adapted to project up through a suitable aperture 89a in the radial arm 15. The upper end of the pin 89 is adapted to abut against the underside of a circular knurled cam head 90 integral with the upper end of a vertical stud 91 swiveled in the radial arm 15. The underside of the knurled cam head 90 is provided with a cam face having a flat low section 92 and a flat high section 93 connected by inclined sections 94. When the head 90 is rotated so that the low flat section 92 registers with the upper end of the pin 89, the arm 18 will be rocked downwardly in a counter-clockwise direction as viewed in Fig 2 about its pivot pin 71, and the recording head 18 will be 10 maintained in an elevated position, holding the needle 19 out of contact with the record 14. When, however, it is desired to cause the recording stylus 19 to engage the surface of the record, it will only be necessary to rotate the cam head 20 90 until the high flat section 93 is positioned in alignment with the pin 89. The arm 18 will then be permitted to rock freely in a clockwise direction and allow the head 18 to move into recording position. 25

The pressure of the stylus 19 upon the record may also be adjusted by means of a solid knurled nut 95 which may be manually moulded along the length of a threaded rod 96 extending from the outer face of the recording head 18. Thus, 30 by moving the nut 95 outwardly upon the rod 96, the force exerted by the stylus needle 19 upon the record 14 will be increased, but when the weight is moved inwardly, the reverse action will occur. It is to be understood, however, that if 35 desired, the knurled solid nut 95 may be omitted, as when the head 18 is cutting the surface of a cellulose acetate record, in which case the force with which said head engages the record surface may be controlled entirely by means of the spring 40 81. In case it is desired to record sound on an aluminum or other metal record, the solid nut 95 will generally be employed as it will assist in obtaining the greater pressure required.

As shown in Fig. 1, an electrical conductor 45 cord 97 is provided for connecting the recording head 18 with a prong plug 98 which is adapted to be inserted in a suitable socket 99 connected to an amplifier or any other suitable source of electrical vibrations.

While there has been disclosed in this specification one form in which the invention may be embodied, it is to be understood that this form is shown for the purpose of illustration only, and that the invention is not to be limited to the 55 specific disclosure but may be modified and embodied in various other forms without departing from its spirit. In short, the invention includes all the modifications and embodiments coming within the scope of the following claims. 60

Having thus fully described the invention, what is claimed as new and for which it is desired to secure Letters Patent, is:

1. In a sound recording mechanism, a disk record turntable, a swinging recording arm extending over said table, feed means to swing said recording arm slowly over the surface of the record to be recorded, said feed means including a driven spindle, a hub, relatively weak friction slipping means for connecting said hub 70 with said arm, and relatively strong friction means for braking said hub, whereby said arm may be swung with respect to said hub without introducing backlash in said feed means.

2. In a sound recording mechanism, a disk rec- 75

- ord turntable, a swinging recording arm extending over said table, feed means to swing said recording arm slowly over the surface of the record to be recorded, said feed means including a driven spindle, a hub, relatively weak friction slipping means for connecting said hub with said arm, relatively strong friction means for exerting a braking action upon said hub, whereby said arm may be swung with respect to said hub without introducing backlash in said feed means, and spring means associated with said spindle for varying the pressure on said strong friction slipping means.
3. In a sound recording mechanism, a disk record turntable, a swinging recording arm extending over said table, feed means to swing said recording arm slowly over the surface of the record to be recorded, said feed means including a driven spindle, a hub, relatively weak friction slipping means for connecting said hub with said arm, and relatively strong friction means for connecting said hub with said feed means, whereby said arm may be swung with respect to said hub without introducing backlash in said feed means, and adjustable spring means associated with said spindle for varying the pressure on said strong friction slipping means.
4. In a sound recording machine, a power driven spindle, a turntable mounted for rotation with said spindle, a recording arm for swinging across said turntable, a speed reduction feed mechanism for driving said swinging arm, a weak friction connection between said feed mechanism and said arm to permit said arm to be manually swung about its axis to any desired point on the record, and a relatively strong friction brake for said feed mechanism to prevent backlash therein and permit the recording to be resumed without delays occasioned by the taking up of backlash.
5. In a sound recording machine, a power driven spindle, a turntable mounted for rotation with said spindle, a swinging arm extending across said turntable, a continuously driven speed reduction feed mechanism connected to said spindle and said swinging arm, a relatively weak friction means for driving said arm from said feed mechanism, and a relatively strong braking means for said feed mechanism to permit said arm to be manually swung about its axis to any desired point without introducing backlash into said feed mechanism which would have to be taken up before again recording.
6. In a sound recording machine, a power driven spindle, a turntable mounted for rotation with said spindle, a swinging arm adapted to extend across said turntable, a speed reduction feed mechanism, a relatively weak friction driving connection between said spindle and said arm, and a relatively strong braking means for said

spindle to permit said arm to be manually swung about its axis to any desired point without introducing backlash into the mechanism for driving said spindle.

7. In a sound recording machine, a frame, a record supporting turntable rotatable adjacent said frame, a driving spindle for operating said turntable, a swinging arm having a recording head at its free end supported adjacent said record, a feed mechanism, a relatively weak friction slipping means for driving said swinging arm from said feed mechanism and permitting said arm to be manually positioned at any desired point, and a relatively strong braking means for said feed mechanism to prevent backlash therein and permitting the recording to be resumed at any desired point without introducing delay occasioned by the taking up of backlash.

8. In a sound recording machine, a power-driven spindle, a turntable mounted for rotation with said spindle, a pivoted recording arm adapted to swing across said turntable, a speed reduction feed mechanism connected to said spindle and said swinging arm, said mechanism comprising two speed reductions connected in series, the final reduction including an intermeshing worm and gear, a relatively powerful friction slipping means applied to said gear to take up backlash in the transmission, and relatively weak friction slipping means for causing said recording arm to be driven from said gear and permit said arm to be moved to any desired point on the record without introducing delay when recording is resumed due to the taking up of backlash.

9. In a sound recording mechanism, a disk record turntable, a swinging recording arm extending over said table, feed means to swing said recording arm slowly over the surface of the record to be recorded, said feed means including a driven spindle, relatively weak friction slipping means for connecting said spindle with said arm, and relatively strong friction means for braking said spindle, whereby said arm may be swung with respect to said spindle without introducing backlash in said feed means.

10. In a sound recording mechanism, a disk record turntable, a swinging recording arm extending over said table, feed means to swing said recording arm slowly over the surface of the record to be recorded, said feed means including a driven spindle, relatively weak friction slipping means for connecting said spindle with said arm, relatively strong friction means for exerting a braking action upon said spindle, whereby said arm may be swung with respect to said spindle without introducing backlash in said feed means, and spring means associated with said spindle for varying the pressure on said strong friction slipping means.

LINCOLN THOMPSON. 60
